UNITED STATES PATENT OFFICE

NATHAN ROBIN, OF CHICAGO, ILLINOIS

DESIGN FOR A TOP FOR A GAME TABLE OR SIMILAR ARTICLE

Application filed October 10, 1932. Serial No. 45,284. Term of patent 3½ years.

To all whom it may concern:

Be it known that I, NATHAN ROBIN, a citizen of the United States, residing at Chicago, in the county of Cook and State of Illinois, have invented a new, original, and ornamental Design for a Top for a Game Table or Similar Article, of which the following is a specification, reference being had to the accompanying drawing, forming a part thereof.

In the drawing:

The figure is a perspective view of a top for a game table or similar article embodying my new design.

I claim:

The ornamental design for a top for a game table or similar article, as shown.

NATHAN ROBIN.
